CLAIM

The ornamental design for a container lid, as shown and described.

DESCRIPTION

FIG. 1 is a top, front, right-side, perspective view of a container lid;

FIG. 2 is a bottom, rear, left-side, perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

In the drawings, the broken lines showing portions of the container lid form no part of the claimed design.

1 Claim, 5 Drawing Sheets
